US0D1114092S

(12) **United States Design Patent** (10) Patent No.: **US D1,114,092 S**
(45) Date of Patent: ** *Feb. 17, 2026

(54) **TOY FIREARM**

(71) Applicant: **FABBRICA D'ARMI PIETRO BERETTA S.P.A.**, Brescia (IT)

(72) Inventors: **Marco Martelli**, Brescia (IT); **Daniele Enoletto**, Brescia (IT)

(73) Assignee: **FABBRICA D'ARMI PIETRO BERETTA S.P.A.**, Brescia (IT)

(*) Notice: This patent is subject to a terminal disclaimer.

(**) Term: **15 Years**

(21) Appl. No.: **35/518,646**

(22) Filed: **Sep. 21, 2023**

(80) **Hague Agreement Data**

Int. Filing Date: **Sep. 21, 2023**

Int. Reg. No.: **DM/231979**

Int. Reg. Date: **Sep. 21, 2023**

Int. Reg. Pub. Date: **Oct. 13, 2023**
